FORM TIE FOR WALL STRUCTURES

Lawrence H. Umbach, Chicago, Ill., assignor to
Universal Form Clamp Co., Chicago, Ill., a
corporation of Illinois

Application February 23, 1931. Serial No. 517,646

2 Claims. (Cl. 25—131)

This invention relates to form clamps for use in connection with the forms employed in the construction of concrete walls.

Concrete walls are usually constructed in 5 wooden forms which are dismantled after the concrete has hardened sufficiently to be self-sustaining. These walls are often built to a considerable height or vertical depth and, therefore, it becomes necessary to hold the forms rigidly in 10 place against inward compression and spreading in order that the finished concrete may assume the desired shape.

Form ties for wall structures usually include an intermediate tie rod and a pair of end bolts alined 15 axially and detachably connected together by coupling nuts of various kinds. The intermediate tie rod is arranged so as to extend between the side members of the form and is left embedded in the concrete after the form is dismantled. The end bolts are usually provided 20 with clamping means at their extremities for securing the form against spreading, and after the concrete has set, the end bolts and couplings are removed when the forms are dismantled. 25 The couplings are usually threaded on the ends of the intermediate tie rod.

Considerable difficulty has been experienced in removing the couplings after the concrete has set because the concrete, while hardening, exerts a 30 great deal of pressure on the couplings and tends to bind them to the tie rod. It is, therefore, desirable to slightly loosen the coupling from the concrete by partially unscrewing it before the concrete has completely set and before the forms 35 are dismantled. With the common type of form tie heretofore in use, any loosening of the couplings would expand the form tie with the result that the form sides would be spread apart.

The main objects of this invention are to provide 40 a form tie having an improved form of coupling; to provide an improved form of end bolt for attachment to the coupling; and to provide a form tie of this kind wherein the couplings may be loosened from the concrete before removal of the forms without altering the length of the form tie.

Illustrative embodiments of this invention are shown in the accompanying drawing, wherein:—

Figure 1 is a vertical transverse section of a 50 concrete wall to which one of the improved ties is applied.

Fig. 2 is an enlarged axial section of one end 55 of the form tie shown in Fig. 1, part of the form being also shown.

Fig. 3 is a view similar to Fig. 2, but showing a modified form of coupling nut.

Figs. 4 and 5 are details, in elevation, showing two different types of clamps for use on the outer ends of the end bolts.

In the construction shown, the improved form tie is applied to the customary type of wall form comprising side members 1, studs 2 and battens 3.

In the form shown, in Figs. 1 and 2, each of the improved ties comprises an intermediate tie 65 rod 4 and a pair of end bolts 5 alined axially and detachably secured together by coupling nuts 6.

The tie rod 4 is shorter than the distance between the form sides 1 and the ends of the rod are threaded with the usual right-hand threads 70 for engagement with corresponding threads on the nuts 6. This construction permits the nuts to be readily adjusted relative to the tie rod and to each other.

The outer ends of the bolts 5 may be provided 75 with any one of various clamps to secure the form against spreading. In the construction shown in Figs. 1, 2 and 3, the end clamps include washers 7 and nuts 8. The end clamp shown in Fig. 4 comprises a collar 9 embracing the bolt 80 and provided with a set screw 10 for locking the collar to the bolt.

The clamp illustrated in Fig. 5 includes a bearing plate 11 and wing nut 12.

Heads 13 are formed on the outer extremities 85 of the bolts 5 to permit the bolts to be gripped by a wrench. The inner extremities of the bolts 5 are threaded with right-hand threads which engage corresponding right-hand threads in the couplings so that, by applying a wrench to the 90 heads 13, the end bolts may be properly adjusted.

In the construction shown in Figs. 1 and 2, the coupling nuts serve as spacers for spacing the form sides 1 the required distance apart. The coupling shown in Figs. 1 and 2 has a tapered 95 body 14 and an integral shank 15, having a central bore 16. The outer end of the body 14 forms an annular bearing face 17 for engaging the inner surface of the form 1 and the shank 15 is adapted to project through an opening 18 in the side 100 member 1.

The bore of the tapered body 14 is threaded with the customary right-hand threads 19 for engaging the tie rod 4 and the bore of the shank 15 is also provided with right-hand threads 20 105 for engaging the corresponding threads on the inner end of the bolt 5. A head 21 is formed on the outer end of the shank 15 to permit the application of a wrench for rotating the coupling.

The coupling nut illustrated in Fig. 3 is simi- 110

lar in all respects to that shown in Figs. 1 and 2 except that the bearing face 17 is omitted and, therefore, the nut cannot serve as a spacer for the sides of the mold. With such a construction, separate spacing means should be employed for securing the form sides against inward movement. The nut shown in Fig. 3 comprises a shank 22 having a bore which is provided with right-hand threads 23 at its inner end and right-hand threads 24 at its outer end. The inner end of the shank, which is adapted to be embedded in the concrete, is tapered and its outer end is provided with a head 25 for the application of a wrench.

15 In operation, the tie rod and end bolts are supported on the form in the manner illustrated in Fig. 1 during the pouring of the concrete. Before the concrete has completely set and while the form sections are still in place, the coupling nuts 20 are slightly loosened from the concrete by applying a wrench to the heads 21 or 25. With the construction shown in Fig. 3, the coupling nuts may be completely removed from the concrete before removal of the form but, with the construction 25 shown in Figs. 1 and 2, in which the coupling nuts serve as spacers, it is necessary to dismantle the form before removing the coupling nuts. With the construction illustrated in Fig. 3, the coupling nuts 30 may be rotated in either direction while the parts are assembled, without in any degree expanding or contracting the form tie. This feature is of great advantage in the construction of concrete walls because it permits the couplings to be loosened from the concrete without removing 35 or loosening the form.

Although but one specific embodiment of this invention has been herein shown and described, it will be understood that certain details of the construction shown may be altered or omitted without departing from the spirit of this invention as 80 defined by the following claims:

I claim:

1. The combination with a wall form having a side member, of a form tie comprising a tie rod and an end bolt alined axially, form clamping means on the outer end of said end bolt, and a coupling unit extending through said form side member and comprising a shank having a axial bore for receiving the adjacent ends of said rod and bolt, one end of said shank having a polygonal head projecting outwardly beyond said side member to permit the application of a wrench for loosening said coupling nut without disturbing said form side. 85

2. The combination with a wall form having a side member, of a form tie comprising a tie rod and an end bolt alined axially, form clamping means on the outer end of said end bolt, and a coupling nut threaded on the adjacent ends of said tie rod and end bolt, the threads being arranged to permit rotation of said coupling nut without altering the length of the form tie, one end of said coupling nut projecting outwardly beyond said form side member to form a head for receiving a wrench whereby said coupling nut 100 may be shifted outwardly relative to said rod without disturbing the form. 90
